SELF-LOCKING SLIDER FOR SLIDE FASTENERS

Filed July 19, 1939

UNITED STATES PATENT OFFICE

2,214,705

SELF-LOCKING SLIDER FOR SLIDE
FASTENERSAlfred E. Carlile, Meadville, Pa., assignor to Talon,
Inc., a corporation of Pennsylvania

Application July 19, 1939, Serial No. 285,375

5 Claims. (Cl. 24—205.5)

This invention relates to slide fasteners and, in particular, to the provision of an improved self-locking slider therefor.

It is an object of this invention to provide an improved lock slider construction of the general type described in U. S. Letters Patent No. 1,853,634, granted April 12, 1932, to Samuel H. Norton, which is smoother and more silent in operation.

10 It is a further object of this invention to provide such a construction wherein distribution of wear upon the slider in operation is substantially improved because of the provision of substantial three-point contact between each stringer and surfaces of the slider channel in which the slide fastener members of the stringer are slidably received.

15 It is a further object of this invention to provide such a construction wherein the application of stringer straightening forces to the fastener will cause locking of the slider against accidental longitudinal movement with respect to the associated stringers through contact of the fastener members with the diamond or wedge of the slider rather than with the flanges, flange ends or projections, as in former constructions.

20 It is a further object of this invention to provide such a slider construction embodying locking area which is substantially increased over the locking area provided in prior self-locking slider constructions between the slider and the fastener members of the stringers.

25 It is a further object of this invention to provide such a construction accomplishing substantial reduction of wear upon the stringers due to the obviation of abrupt curving, flexing, or bending of the stringers and stringer cords within the slider channel whereby substantially to decrease the wear upon the cord and the stringers.

30 It is a further object of this invention to provide such a slider construction embodying simplicity of design, great strength, rigidity and durability because of the provision therein of relatively thick walls or flanges, and relatively large and strong wedge or diamond.

35 It is a further object of this invention to provide such a slider construction which is particularly adapted to plastic molding and metallic die casting methods of manufacture.

40 These and other objects and advantages of the invention will appear from the following description taken in conjunction with the accompanying drawing which forms a part thereof, and will be pointed out in the appended claims.

45 In the drawing:

Fig. 1 is a plan view of the lower portion of a slide fastener embodying my slider construction as a component part;

Fig. 2 is an enlarged transverse section taken substantially on the line 2—2 of Fig. 1;

Fig. 3 is a longitudinal section taken substantially on the line 3—3 of Fig. 2 and showing the position taken by the parts when longitudinal force is applied to the slider;

Fig. 4 is a view similar to Fig. 3 but showing 10 the position taken by the parts when transverse separating force is applied to the slide fastener stringers above the slider; and

Fig. 5 is a view similar to Figs. 3 and 4 but showing the position taken by the parts when 15 transverse separating force is applied to the slide fastener stringers adjacent the slider.

Referring to the drawing in detail and with reference particularly to Fig. 1 wherein, for the purposes of illustration only, I have shown the 20 application of my improved slider to an otherwise conventional slide fastener of the non-separating type, the slide fastener stringers, which are generally designated 10, comprise tapes 11 of suitable material, preferably reinforced at one 25 edge 12, and having secured to the reinforced edge 12 in suitable spaced relationship fastener members 14 which are adapted for interengagement in known manner to secure the adjacent edges of the stringers 10 together. The lower 30 ends of the reinforced edges 12 of the stringers 10 are secured together by suitable bottom stop means such as the fixed or non-separating bottom stop 15.

The slider is generally designated 16 and is 35 preferably, though not necessarily, of integral construction. The slider body comprises the rear or back wing 14 and forward or front wing 18 which are secured together in parallel spaced relationship by the wedge member or diamond member 19. The wedge or diamond member 19 cooperates with marginal side flanges 21 on the rear or back wing 17 and marginal side flanges 22 on the forward or front wing 18 to define a substantially Y-shaped slider channel adapted slidably to receive the reinforced edges 12 of the stringers and the attached fastener members 14.

In order that the slider 16 may be readily moved manually longitudinally of the slide fastener stringers, the forward or front wing 18 is provided with a longitudinal recess or channel 23 which extends from end to end thereof and in which there is disposed an elongated, substantially rectangular pull member 24 which has the upper end thereof pivotally secured to the 45

forward or front wing 18 by means of the transverse pin 25 extending through suitable aligned bores provided in the front wing 18 and the pull member 24.

5 The dominant feature of this invention resides in the reversely curved nature of the slider channel. This channel, which is generally designated 26, is formed by the inner lateral surfaces of the pairs of flanges 21 and 22 and the lateral surfaces of the wedge 19. The channel is substantially Y-shaped and comprises a substantially straight throat portion 26a at the lower end of the slider which extends upwardly into two inwardly curving branches 26b which are separated by the wedge 19.

10 Each side flange 21 is separated from the adjacent side flange 22 by a slot 26c which extends laterally from the channel 26, as shown in Fig. 2. These slots are adapted slidably to receive the 15 tapes 11 of the stringers 10.

15 The inner lateral surfaces of the side flanges 21 and 22 are reversely curved, as shown in Figs. 3 to 5, in such manner that the inner lateral surface portions defining the throat portion 26a 20 of the channel 26 are substantially straight or flat while the inner lateral surface portions defining the branches are concave, as shown in Figs. 3 to 5 inclusive. The lower or inner lateral surface portions of the wedge 19 are convex and 25 are substantially parallel with the adjacent complementary branch-forming concave lateral surfaces of the flanges 21 and 22.

30 The upper inner corners of the side flanges 21 and 22 are rounded or bevelled to prevent wedging engagement or ratcheting between the outer ends or leg portions of the fastener members 14 and these upper portions of the side flanges.

35 It will thus be seen that the slider channel is reversely curved and the upper diverging branches thereof are curved inwardly toward one another at the top of the slider. Because of this curvature in the branches of the slider channel, the locking engagement between fastener members 14 and the slider is accomplished 40 because of the inwardly directed thrust exerted upon the fastener members disposed at the intermediate portion of each branch upon the application of transverse forces to the stringers above or below the slider which tend to stretch 45 or straighten the reinforced edges 12 of the stringers.

50 In Fig. 3, the position of parts is illustrated wherein no substantial transverse forces exist and wherein the slider 16 is freely slideable longitudinally of the stringers 10. It will be seen in Fig. 3 that the head portions of the fastener members 14 ride freely over the surface of the wedge or diamond member 19 while the rear portions or leg portions of the members 14 slide 55 freely over the curved surfaces between the straight throat portion 26a and the branches 26b and over the rounded or bevelled upper inner corners of the flanges 21 and 22, as described above. There is, therefore, substantially three- 60 point contact between the fastener members 14 on each stringer and the engaged slider surfaces. In each case, as will be seen from Figs. 3 and 4, the fastener members engaging the surfaces of the wedge member 19 are always disposed upon 65 the bent portion of the reinforced edge 12 of the stringers.

70 The application of any transverse force to the stringers, either above the slider as in Fig. 4 or in line with the slider as in Fig. 5, will cause a 75 locking engagement. Where the transverse force

is disposed either above or below the slider, the locking engagement occurs because of the tendency toward straightening of the reinforced edges 12 and consequent application of inward force to the fastener members engaging the 80 wedge 19.

85 Where the transverse force is in line with the fastener, as in Fig. 5, the fastener members in the intermediate portion of the curved slider channel branches are caused to seek the line 90 of least resistance, as does a marble in a bowl, whereby they take the position illustrated in Fig. 5. The locking effect in this last case is accomplished independently of engagement of the fastener members 14 with the wedge 19, as shown. 15

95 In Figs. 4 and 5, the fastener members 14 within the throat and branches of the channel 26 are designated 14a to 14i respectively. It will be seen that where a straightening force is applied to the reinforced edges of the stringers, as in 20 Fig. 4, the fastener members 14c, 14d, and 14e, which are within the inwardly curved diverging branches of the channel, are thrust inwardly against the surface of the wedge 19. The curvature of the upper inner corners of the side flanges 25 21 and 22 prevents undue interference with the leg portions of the fastener members and, also, the application of undue friction to the portions of the reinforced edges 12 disposed between adjacent fastener members 14, as the fastener 30 members 14 and 14b of Fig. 4.

35 The gentle curvature of the portion joining the throat portion 26a and the branches 26b of the channel causes free sliding movement between the leg portions of the fastener members and the slider. In the position of parts illustrated in Fig. 4, the leg portion of the fastener member 14a are 40 rockingly supported on the upper inner corner of the left side flange 22. The fastener member 14b is substantially free while the head portion of the fastener member 14c lightly engages the surface of the wedge 19. The fastener members 14d and 14e are thrust inwardly with substantial force, as indicated by the arrows, while the fastener member 14f has a corner of the leg 45 portion in engagement with the inner surface of the right side flange 22, which tends to cause rotation thereof in the direction of the arrow. The fastener members 14g, 14h and 14i are 50 thrust outwardly, slightly, toward the inner surfaces of the side flanges in the throat portion 26a of the channel 26.

55 In the position of parts shown in Fig. 5 where- 60 in the transverse force is exerted substantially in a line through the inwardly curved diverging branches of the channel 26, the thrust exerted upon each of the fastener members 14 is shown by the arrows, and it will be seen that the locking effect is achieved mainly by contact of the fas- 65 tener members 14c, 14d and 14e in the concave surface portions of the side flanges 21 and 22. The fastener member 14e has a slight clockwise torque exerted thereon while a similar counter- 70 clockwise torque is exerted on the fastener mem- 75 ber 14b. A slight counter-clockwise torque is exerted on the fastener member 14g while a re- 80 verse or clockwise torque is exerted on the fastener member 14f. The fastener members 14h and 14i, which are disposed in the throat por- 85 tion 26a of the channel 26, are subjected only to a slight outward thrust against the channel walls of the throat portion. In this case, it is to be 90 noted that the fastener members are all free of contact with the wedge 19. 95

It is to be noted that in each position of the parts, substantial area of contact is provided between the various surfaces of the fastener members and the various interior surfaces of the slider. It is also to be noted that there are no abrupt bends or curves in the interior slider surfaces and that, for that reason, the slider is extremely free running, being subjected to relatively no undue friction, clicking, and ratcheting, such as is common in such prior, inherently locking slide fastener slider constructions wherein such surfaces or projections are found.

It is, of course, to be understood that the above described structure is merely illustrative and in no wise limiting and that I desire to comprehend within my invention all modifications included within the scope of the appended claims.

Having thus fully described my invention, what I claim as new and desire to secure by Letters Patent is:

1. In a slider for slide fasteners, a slider body having therein a slider channel comprising a straight throat portion having upwardly diverging curved branches leading therefrom, the upper ends of said curved branches being directed inwardly toward one another and the upper outer corners of said branches being rounded for preventing ratcheting between the slider and fastener members passing through said branches.

2. In a slider for slide fasteners, a slider body comprising a pair of wings having marginal side flanges and a wedge member connecting the upper ends of said wings and disposed within said flanges, the inner surfaces of said flanges being reversely curved and cooperating with said wedge to form a slider channel comprising a straight throat portion and upwardly diverging branches of slight curvature leading from said throat portion, said branches having their upper terminal portions inclined inwardly toward one another, and said wedge member having its widest portion adjacent its lower end and aligned substantially with the widest spaced portions of the inner surfaces of said marginal side flanges.

3. In a slider for slide fasteners, a slider body comprising a pair of wings having marginal side flanges and a wedge member connecting the upper ends of said wings and disposed within said flanges, the surfaces of said wedge member within said flanges being convex and of gradual curvature, the lower portions of the inner surfaces of said flanges being straight and forming a straight channel throat, and the upper portions of said inner flange surfaces being concave and forming with the curved surfaces of said wedge upwardly diverging curved branches leading from said channel throat and inwardly directed toward one another at their upper ends, and the upper inner corners of said marginal side flanges being rounded for reduction of friction between said slider and fastener members in said channel.

4. In a slider for slide fasteners, a slider body comprising a pair of wings having marginal side flanges with reversely curved inner surfaces, and a wedge member joining said wings with its widest portion adjacent its lower end, in alignment with the widest spaced portions of the inner surfaces of said side flanges, and having curved outer surfaces disposed within said flanges, said slider body having therein a slider channel formed by said wedge and said flanges and comprising a straight throat portion having upwardly diverging curved branches leading therefrom, said throat portion and said diverging channel branches being joined by surfaces of gradual curvature and cooperating with fastener stringers within said channel to convert stringer straightening stresses into inward thrust upon fastener members of said stringers toward the curved surfaces of said wedge for frictionally locking said slider with respect to said slider stringers.

5. A slider construction as defined in claim 4, the upper inner corners of said marginal side flanges being rounded for reduction of friction between said slider and fastener members in said channel.

ALFRED E. CARLILE.
